UNITED STATES PATENT OFFICE.

GILBERT H. BLAKESLEY, OF BRISTOL, CONNECTICUT.

DESIGN FOR A GARTER.

SPECIFICATION forming part of Design No. 29,204, dated August 9, 1898.

Application filed August 13, 1897. Serial No. 648,176. Term of patent 14 years.

To all whom it may concern:

Be it known that I, GILBERT H. BLAKESLEY, of the town of Bristol, in the county of Hartford and State of Connecticut, have invented and produced a new and original Design for a Garter, of which the following is a specification, reference being had to the accompanying drawing, forming a part thereof.

The drawing represents my design of a garter in perspective.

The leading features of my design consist in the general configuration and shape of the garter, substantially as herein described.

The figure of the drawing represents the garter in perspective, and referring particularly thereto it will be seen that the body or main part of the garter A forms a circle and is uniform in width. At the front the body part, as shown, is broken, and there is shown

between the ends round parts B and C C, the 20 part B being straight and much larger than C C and the parts C C being oblique.

The leading feature of my design, however, is the substantially circular body part with the front showing ends joined by two different sized parts, one straight and the other oblique. 25

Having thus described my invention, what I claim is—

The design for a garter substantially as 30 herein shown and described.

In testimony whereof I have signed this specification in the presence of two subscribing witnesses.

GILBERT H. BLAKESLEY.

Witnesses:

THOMAS A. TRACY,
JOHN J. JENNINGS.
